POWER OPERATED CHAIN SAW

David T. Doman, Fayetteville, N. Y., assignor to Porter-Cable Machine Company, Syracuse, N. Y., a corporation of New York

Application May 12, 1954, Serial No. 30,423

Term of patent 14 years

(Cl. D93—3)

Des. 175,825

PAGE 2

FIG. 2

FIG. 3

Figure 1 is a top plan view of a power operated chain saw embodying my new design.

Figure 2 is a perspective view of the right side of the machine shown in Figure 1.

Figure 3 is a perspective view of the left side of the machine shown in Figure 1.

I claim:

The ornamental design for a power operated chain saw, as shown.
